UNITED STATES PATENT OFFICE.

CHARLES F. MITCHELL AND CHARLES R. BOESCHE, OF BALTIMORE, MARYLAND.

IDENTIFICATION TAG.

Application filed April 4, 1922. Serial No. 549,400.

To all whom it may concern:

Be it known that CHARLES F. MITCHELL and CHARLES R. BOESCHE, citizens of the United States, residing at Baltimore, in the State of Maryland, have invented certain new and useful Improvements in Identification Tags, of which the following is a specification.

This invention relates to improvements in identification tags such as laundry tags which may readily be clipped to articles that are to pass through a public laundry during the washing or ironing thereof so that the owner of each article may readily be identified.

The object of the invention is to provide an improved construction of tag that may readily be clipped to a fabric article that is to be laundered without injury to the latter and which because of a number it bears will indicate the owner, whereby the articles need not be permanently marked with indelible ink which mars the appearance of the article.

With these objects in view, the invention is illustrated in the accompanying drawing, wherein,—

Fig. 1 shows the improved tag attached to an article to be laundered as viewed from one side thereof.

Fig. 2 illustrates the same as viewed from the reverse side thereof.

Fig. 3 shows the detached tag spread open and in perspective.

Fig. 4 illustrates an enlarged sectional detail through the latch-holding device—the section being taken on the line 4—4 of Fig. 1.

Fig. 5 shows an enlarged vertical cross-sectional detail through secured-together tag parts as the same would appear if cut on the line 5—5 of Fig. 1, and

Fig. 6 illustrates the secured-together tag parts looking at that edge where the locking bar is carried and engaged.

In carrying out our invention we make use of two plates one of which is designated 10, and may be termed the tongue-plate while the other is designated 11 and may be termed the clamp-plate.

The tongue-plate 10, is provided with a slot 12, and one wall of this slot has engaging-means 13 projecting from one edge thereof and in a direction that we term inwardly, because said engaging-means extends toward the clamping-plate. The

tongue-plate also has an intermediate cross-slot 14 extending crosswise thereof and from the opposite ends of this cross-slot said plate has segment slots 15 and 16 respectively. 60

At the point where the cross-slot 14, is located the tongue-plate is bent rearwardly to form a crosswise extending off-set 17 of a depth about equal to the thickness of the plate itself, for a purpose that will presently be explained.

Adjacent to the ends of the slots 15 and 16 the tongue-plate is notched at one edge whereby to produce two edge or corner-lugs 18 and 19 respectively, and the lug 19, is provided with a locking recess or perforation 20, for a purpose that will presently be explained.

To the lug 18, there is pivotally attached, at 21, one end of a locking-bar 22, which latter is provided midway between its ends with an off-set portion 23, also for a purpose that will presently be explained.

The free-end 24 of the locking bar has a depression 25, punched therein from one side which produces a rounded projection 26 on the opposite side which latter will register and snap into engagement with the locking recess or perforation 20 in corner-lug 19 of the tongue-plate when said bar is swung around to the locking position shown in Figs. 1—2—4 and 6 of the drawings.

The clamp-plate 11, is provided with a slot 27 which registers with the slot 12 and the engaging-means 13 of the tongue-plate, 90 as clearly shown in Fig. 5, of the drawing, and said clamp-plate also has a cross-bar 28, which is separated from the clamping portion of the plate by horizontal edge notches or slots 29 so that the metal 30, left in the clamp-plate between the inner ends of the notches or slots 29 will be sufficiently narrow to pass through the intermediate cross-slot 14 of the tongue-plate. The clamp-plate is bent forwardly along a horizontal line through the metal 30 to produce a forwardly-extending cross-wise off-set 31, of a depth substantially equal to the thickness of the plate itself, as clearly shown in the sectional view of Fig. 5, so that the rearward off-set 17 of the tongue-plate and the forward off-set 31, of the clamp-plate occur at the slot 14 of the tongue-plate and the edge notches or slots 29 of the clamp-plate.

100 It will be noted that the cross-bar 28 of the clamp-plate is of less width in a hori-

zontal direction than the distance between the lowermost ends of the segment slots 15 and 16 in the tongue-plate so that if the metal in the tongue-plate be sprung inwardly, or to the right hand as viewed in Fig. 3 of the drawing, a vertical gap of sufficient width will be produced to permit the cross-bar 28 to be passed down and forwardly-through said gap so that the upper 10 or clamping portion of the clamp-plate will have position at one face of the tongue-plate while the lower portion of said clamp-plate will have position against the opposite face of the said tongue-plate. The effect therefore of this construction is to pivotally connect said two plates by passing one through the slot 14 of the other,—the two off-sets 17 and 31 permitting this to be done while allowing the adjacent clamping ends of said plates to be swung into a substantially parallel position to clamp a fabric article that may be inserted between them.

Below the cross-bar 28, the clamp-plate has a central latch-tongue 32 of less width 25 than the cross-bar which extends down between the two corner-lugs 18 and 19 of the tongue-plate and said latch-tongue 32, is so positioned as to lie in a plane substantially flush with the two ends of the pivoted latch-bar 22, whereby the off-set central portion 39 of said latch-bar will overlie the latch-tongue 32, and lock it in a position to hold the clamp-plate and tongue-plate in the clamping position as shown in Figs. 1—2—5 and 6 of the drawing.

To attach the tag to a fabric article 33, the same will be opened as shown in Fig. 3, and the spread-apart plates will be placed over an edge of the fabric. The latch-tongue 32, will then be swung to a position between the corner-lugs 18 and 19, which movement will swing the clamp-portions of the tongue-plate and the clamp-plate into clamping engagement with the interposed fabric. The 40 latch bar will then be swung around so that the central off-set 23, will overlie the latch-tongue 32 and when the free end 24 of said

latch-bar passes under the corner lug 19, as in Fig. 1, its projection 26, will snap into the recess or perforation 20 of the lug and 50 hold the parts in the clamped position.

When in the clamped position, the engaging means 13 of the tongue-plate will press the fabric into the slot 27 of the clamp-plate without however puncturing the fabric 55 but with sufficient gripping action to secure the tag to the fabric.

Each tag will bear a number assigned to a customer so that identification of ownership can readily be established.

Having described our invention, we claim,—

1. In an identification tag the combination with a clamping plate having a cross-slot with a slit in the plate at each end of the slot whereby the metal of the plate bounded by the slot and the two slits may be temporarily bent to one side, of a second clamping plate having one end thereof inserted through the slot of the first-named plate and pivotally retained therein by the metal of the said first-named plate that is bounded by said slot and slits whereby to form a clamp and means to hold the two plates 70 clamped.

2. In an identification tag the combination with a clamping plate having a cross-slot and provided with a slit at each end of the cross-slot said plate also having two spaced-apart lugs, of a second clamping plate extending through the cross-slot of the first-named plate and having a latch-tongue on the inserted end thereof which projects between the said two lugs of the first-named plate the said two plates being pivotally engaged by the bearing of one on the other at the edge of the cross-slot, and means extending from the lug of one plate and engaging the latch tongue of the other plate for holding the plates clamped together.

In testimony whereof we affix our signatures.

CHARLES F. MITCHELL.
CHARLES R. BOESCHE.
